UNITED STATES PATENT OFFICE

MARIUS S. DARROW, OF ST. LOUIS, MISSOURI, WILLIAM J. HART, OF EAST ST. LOUIS, ILLINOIS, FRED G. GRONEMEYER, OF ST. LOUIS, MISSOURI, AND FRANCIS B. WATKINS, OF EDWARDSVILLE, ILLINOIS, ASSIGNEES TO THE BARBER ASPHALT COMPANY, OF PHILADELPHIA, PENNSYLVANIA, A CORPORATION OF WEST VIRGINIA

MACHINERY FOR MANUFACTURING SHINGLES

Application filed July 24, 1926. Serial No. 124,578.

This invention relates to machinery useful in the manufacture of roofing shingles more particularly of the type adapted for diagonal laying and characterized by under-folded corners with attached staple-like securing devices. Such shingles are ordinarily known in the trade as "Latite" shingles, and have been extensively manufactured by the machine shown and described in United States Patent No. 1,522,234 to William Freegard and Marius S. Darrow, dated Jan. 6, 1925. While with this machine the operations of stapling and folding are accomplished continuously and automatically, the pre-cut shingle blanks had to be fed to it individually and by hand, thereby entailing constant attention on the part of an operative.

The present invention is directed toward overcoming the disadvantages of hand feeding by provision of automatic mechanism capable of forming and continuously feeding the shingle blanks from a continuous sheet or web and delivering them to the stapling and folding mechanisms of the machine for conversion into completed "Latite" shingles ready for immediate packing and shipment.

In the drawings, Fig. I is a plan view of a shingle fabricating machine conveniently embodying the automatic blank forming and feeding mechanism of our invention.

Fig. II is an elevation of the machine as viewed from the bottom of Fig. I.

Fig. III is a partial elevation of the side of the machine opposite to that shown in Fig. II; and,

Fig. IV is a fragmentary elevation viewed in the direction of the arrows IV-IV in Fig. I.

The shingle folding and stapling mechanisms herein comprehensively designated 10 and 11 respectively, will be observed as generally similar to the corresponding mechanisms in the patent to which reference has been made. These folding and stapling mechanisms 10, 11 are moreover actuated, as before, by a drive pulley 12 (Figs. I and III) whereby motion is constantly transmitted, through interposed speed reduction

gearing 13, to the shaft 14 of the upper segmental shingle progressing roll 15 which is attended by a smaller cooperating lower roller 16 with a continuous surface in advancing the shingles S successively to the folding mechanism 10. Intermittent rotary motion is imparted through a mutilated gear 18 and cooperating pinion 19, (Fig. III) from the same source to an upper shaft 20, which, through an eccentric 21, reciprocates the upper stapling die block 22 (Fig. III) relative to the opposing lower stationary die block shown at 23, likewise as in the patent.

Instead of being individually pre-formed and fed to the machine by hand as heretofore, the shingle blanks S are successively fabricated from a continuous sheet or web W (Fig. I) of suitably prepared waterproofed and mineral surfaced material which is drawn forward from a supply roll (not shown) by a pair of superposed draft rollers 25, 25 that are arranged, in the present instance, at an angle of 45° to the longitudinal center line of the machine and suitably journaled in bearings 26 provided by the machine frame. The draft rollers 25 are driven through spur gearing 27—from a shaft 28—that derives motion, in turn, by virtue of bevel gear coupling at 29 with a stub shaft 30 whereon is mounted a spur pinion 31 which cooperates with a second mutilated driving gear 32 on that end of the shaft 14 of the segmental shingle progressing roll 15, appearing in Fig. II. The relation of the intermittent gears 31 and 32 is such that the draft rolls 25 are moved through a complete rotation, at each actuation, for diagonal advancement of the web W to an extent corresponding to the width of a shingle S. As a consequence of such diagonal advancement, the corner C of the web W (Fig. I) is presented between the upper and lower die blocks 22 and 23 of the staple forming and applying mechanism 11, while the yet uncut blank is at the same time properly allocated in readiness to be engaged by the main progressing rollers 15, 16 and passed to the folding mechanism 10.

During the dwell which follows shifting

of the web W as just described, the mechanism 11 is actuated to apply a staple across the forward corner C of the web W in precisely the same manner as set forth in the patent, supra; and the blank shingle S is concurrently severed from the web W by shearing mechanism, which is generally indicated at 34 in Figs. I and IV of the drawings. As shown, this shearing mechanism 34 comprises a pair of opposing cutting blades 35, 36 between which the end of the web W is passed incidental to its feeding, one of these blades 35 being fixedly supported by the machine frame while the companion blade 36 is secured in a movable holder 37 with opposite ends fulcrumed at 38, 38 on said machine frame, and an actuating link connection 39 with an eccentric 40 on the upper shaft 20, hereinbefore referred to.

Immediately upon the consummation of the foregoing contemporaneous operations, the severed shingle blank S is gripped between the progressing rollers 15, 16 and by them advanced to the mechanism 10 for progressive retrovertive bending of the stapled corner C and final scoring of the resulting fold to render the crease permanent.

In lieu of the arrangement of the patent, feeding of the metallic ribbon M from which the staples are formed is preferably effected by actuating means operatively co-ordinated and timed with the drive of the main advancing rolls 15, 16 and the web drawing rollers 25. To this end we provide a pair of superposed nip rollers 45-45, (Figs. I and III) between which the ribbon M is passed enroute from a source of continuous supply not shown, said rollers being intermittently driven, through the medium of speed reducing gears 46 (Fig. I), from a shaft 47 that is dependent for movement upon a bevel gear connection at 48 with one end of a companion shaft 49. At the opposite end, this shaft 49 is co-ordinated, by bevel gearing 50 (Fig. 1), with the shaft 30 of the spur gear 31, previously mentioned.

From the foregoing it will be seen that through our invention, the whole operation of stapled shingle fabrication is rendered continuous and automatic from start to finish to the advantage of obviating irregularities heretofore attendant upon hand feeding, as well as reducing the cost of manufacture to the absolute minimum.

Having thus described our invention, we claim:

1. A shingle manufacturing machine including means for intermittently feeding a strip of material in the direction of its length, a knife arranged to sever the strip on a transverse line to form a shingle therefrom while the strip is stationary, means for operating on a corner of a shingle, and means for intermittently feeding a severed shingle in the direction of its diagonal and

at an angle to the direction of feed of the strip to the said operating means.

2. A shingle manufacturing machine including means for intermittently feeding a strip of material in the direction of its length, a knife arranged to sever the strip on a transverse line to form a shingle therefrom while the strip is stationary, means for stapling a corner of a shingle substantially concurrently with its severing, means for operating on the stapled corner of a shingle, and means for intermittently feeding a severed shingle in the direction of its diagonal and at an angle to the direction of feed of the strip to the said operating means.

In testimony whereof, we have hereunto signed our names at Madison, Ill., this 19th day of July, 1926.

MARIUS S. DARROW.
